CORNER ANGLE SHOWER STALL

Lawrence E. Wolske, Benton Harbor, Mich., assignor to
Whirlpool Corporation, a corporation of Delaware

Filed Sept. 14, 1966, Ser. No. 3,861

Term of patent 14 years

(Cl. D4—4)

FIGURE 1 is a front view slightly in perspective of a corner angle shower stall embodying my new design;

FIGURE 2 is a vertical section taken substantially along the line 2—2 of FIGURE 1, the depth of the design embossment in the bottom wall shown in dotted lines in FIGURES 1 and 3 being insufficient to permit illustration thereof in the small scale illustration of FIGURE 2; and

FIGURE 3 is a top plan view thereof.

The bottom and rear views are omitted as being hidden in normal installation and define no part of the invention.

The dominant features of my invention are shown in solid lines.

I claim:

The ornamental design for a corner angle shower stall, as shown and described.
